UNITED STATES PATENT OFFICE

ROBERT KIRKLAND MILLS, OF SHERWOOD, NOTTINGHAM, ENGLAND

KNITTING MACHINE NEEDLE

Application filed August 19, 1931, Serial No. 558,155, and in Great Britain August 20, 1930.

This invention comprises improvements in the means for and method of producing knitted fabrics and has particular, although not exclusive, reference to the production of a knitted fabric of the type set forth in the specification of prior application No. 419,228, which fabric is locked against roving or laddering by passing predetermined or selected of the intermeshing thread loops through and also closely around other loops.

According to the present invention a needle for use in the production of knitted fabrics is provided with a pivoted latch which has two open positions, one wherein the free end or tip thereof is maintained spaced from the needle shank or stem so as to permit free passage of thread beneath said latch and a second wherein said latch end or tip coacts with the shank so as to permit of a thread loop being passed from the shank over said open latch.

The needle latch may be either flexible or inflexible. In the former case when the flexible or resilient latch is in the normal open position same is spaced at its tip from the needle shank but is adapted to be pressed against its own resilience so that said tip engages a recess or groove in the shank and prevents the passage of thread between the tip and said shank.

Where the pivoted latch is of an inflexible or rigid character, same is spaced at its tip from the needle shank when in the normal open position in a similar manner to the flexible or resilient latch said inflexible or rigid latch when in the second open position, (i. e. fully open) coacting at its tip with a recess in the needle shank and providing between said open latch and shank an enclosed space within which thread fed therein is freely accommodated.

A needle as above with pivoted latch either resilient or rigid is applicable for the production of locked or tied knitted stitches and also of normal or untied stitches; and to this end the invention includes means whereby when a locked stitch is being produced, thread is fed beneath the latch and the open latch pressed or moved to a position wherein its tip engages with the needle

shank and accommodates said thread between said open latch and said shank, and also means whereby when a normal stitch is being produced the thread is fed into the needle hook and the latch operates in the customary manner.

Needles as above can be employed in any customary or existing type of knitting machine, and where such needles are employed the needle-operating cam mechanism is so designed that at predetermined intervals said needles are projected to an extent to permit feeding of the thread within the needle hooks to produce ordinary knitted stitches and at other predetermined intervals to project the needles to an extent sufficient to permit of the thread being fed below the tip of the open latches and produce tied stitches.

For the purpose of more fully describing the nature of this invention reference will now be made to the accompanying drawings, wherein:—

Figures 1 to 4 illustrate four successive steps in the production of a locked or tied knitted stitch by the employment of a needle having a flexible latch.

Figure 5 illustrates diagrammatically an arrangement of knitting cams suitable for producing in succession normal or untied stitches and locked or tied stitches.

Figure 6 is a detail view in plan illustrating means applicable to a circular knitting machine for operating the needle latch pressers.

Figure 7 is an elevational view of Figure 6.

Figures 8 to 11 illustrate four successive steps in the production of a locked or tied knitted stitch by the employment of a needle having an inflexible or rigid pivoted latch.

In one method of carrying out the invention a needle 1 is provided having a pivoted latch 2 which in the normal open position projects out from the needle shank, said latch being flexible or resilient so as to permit of the tip or free end 2a thereof being pressed into a recess or groove 1a formed in the shank. That part of the shank provided with the recess may, if desired, be thickened or increased in width in side elevation in a somewhat similar manner to the part accommodat-

ing the latch pivot, and the construction is such that when the latch 2 is open and the tip 2a thereof pressed into the recess 1a a space exists between the centre portion of the latch and the shank for accommodating a thread or threads. When the latch is in the closed position the tip thereof coacts with the needle hook 3 in the customary manner.

In the process of knitting a locked or tied stitch, the needle constructed as above is raised or projected to an extent sufficient to clear the existing thread loop *a* thereon beneath the recess 1a for accommodating the latch tip 2a, and new thread *b* is fed below the latch 2 as shown in Figure 1. During the downward movement or retraction of the needle a presser 4 is brought into operation to press the latch tip 2a into the recess 1a in the shank as in Figure 2 and permit of the existing loop *a* passing over the latch 2 into the needle hook 3, the newly fed thread meanwhile being retained beneath the latch, as in Figure 3. The continued downward movement of the needle causes the loop of new thread *b* to raise and close the latch, and said loop becomes cast off while the old loop *a* is still retained in the needle hook. In this way the loop *b* of new thread is first drawn through the old loop *a* and then passed closely around same so as to become tied thereon, as will be seen by referring to Figure 4.

In the production of a normal or untied knitted stitch the needle 1 is only raised sufficiently to clear the old loop *a* below the latch 2 and to enable the new thread *b* to be fed into the needle hook 3, the aforesaid latch-pressing means 4 being retained out of operation and the stitch being produced in the customary manner.

The different degrees of motion required to be imparted to the needles may be effected by incorporating in a knitting machine two different types of needle-operating cams, one cam functioning to displace the needles to an extent sufficient to move the tip of the latch above the feeding thread and another cam functioning to displace the needles to an extent sufficient to receive the newly fed thread within the hook.

For example, in a circular knitting machine two needle-operating cam devices such as shown in Figure 5 may be employed, the one cam device A being of the ordinary type as at present employed for producing unlocked stitches, and the other cam device B producing the tied stitches. The direction of traverse of the needles is indicated by the arrow X and the cams A, B are so installed that the needles first traverse the ordinary knitting cam A to produce unlocked or tying stitches and subsequently traverse the cam B for producing the locked or tied stitches, it being, of course, understood that there is a separate thread feed in connection with each cam device, said feed being indicated at 5 and 6. It

will be seen that the cam device B functions to raise or project the needles to a greater extent than the cam device A so that the newly fed thread from the feeder 6 is laid upon the needles beneath the flexible latches 2 as before described.

In a circular machine individual presser members 4 (Figures 1 to 5) are advantageously provided in connection with each flexible latch needle, the upper or latch-engaging part of each member 4 being normally spaced laterally from the needle and being maintained in such position by a coiled spring ring 7 or equivalent means encircling the series of pressers.

When the needle is traversing the locked stitch cam B and is being lowered or retracted by said cam after receiving the newly fed thread *b*, the presser member 4 is engaged by a presser-operating slidable cam member 8 (Figures 2, 6 and 7,) which member pushes the presser 4 on to the needle latch 2 against the influence of the spring band or other means 7 thereby pressing said latch on to the needle shank and permitting the old loop *a* to pass over the pressed latch into the needle hook.

Means may be incorporated for rendering inoperative the latch pressing means as and when required, and one method of accomplishing this is illustrated in Figures 6 and 7 as applied to a circular machine. In this arrangement the presser-operating cam 8 is radially slidable within fixed guides 9 and has at its outer end or part a slot 10 within which operates the upper bevelled or inclined portion 11a of a vertically slidable and guided rod or bar 11 carrying at its lower extremity a truck 12 coacting with a chain, cam drum or equivalent member 13. The upper inclined or bevelled portion 11a of the bar 11 may operate between rollers 14 on the sliding cam 8.

Normally the presser cam 8 is maintained operative, i. e. with its cam face 8a in the path of the presser members 4. When, however, the production of locked or tied stitches is to be discontinued, say for example in the production of the heel and toe portions of a stocking or the like, a high link, cam projection or the like on the chain or member 13 operates on the bar 11 to lift same and in doing so the upper inclined or bevelled portion 11a of the bar effects a withdrawal of the presser cam 8 so as to bring the face 8a out of the path of the presser members 4.

In a modified method of carrying out the invention (see Figures 8 to 11 of the accompanying drawings) the needle 1 is provided with a pivoted latch 2b which is rigid or inflexible. Preferably this rigid latch is provided at or adjacent to its pivot with a small lateral projection or cranked portion 2c.

That part of the latch having the cranked portion 2c is preferably flattened so as to

have a free pivotal movement within a saw-cut 15 provided in the needle shank 1, the remaining portion of the latch being advantageously of rounded cross section.

5 The part 1b of the needle shank which accommodates the latch pivot and is provided with the aforesaid saw-cut 15 is of increased width, as is customary in a latch needle, and spaced a suitable distance below said pivot-accommodating part 1b the needle shank is formed with a second portion 1c of increased width, said latter portion being provided with a saw-cut or recess 16 within which, when the latch 2b is in the fully open or lowered position, the latch tip is freely accommodated. For this purpose the latch tip is preferably formed with a comparatively elongated point 2d which will move freely into and out of the saw-cut 16 provided therefor.

20 Preferably also a cup or recessed portion 2e is formed on the latch adjacent to its pointed extremity 2d, said cup 2e, when the latch is in the raised or closed position, accommodating the extremity of the needle hook 3, which extremity is preferably brought to a comparatively sharp point so as to be well buried in the cup of the latch. When the latch is fully opened or lowered 30 the cup 2e adjacent to its pointed tip 2d constitutes an abutment serving to prevent said pointed tip from projecting too far into or becoming wedged within the saw-cut 16 in the shank.

35 Advantageously, the latch 2b is slightly curved in its length, and the front face of the needle shank, i. e. that face on which the hook and latch are provided, is also curved or concave between the two wider portions 40 1b, 1c of said shank. In this way a substantially elliptical space 17 is provided between the latch 2b and the needle shank when the latch is fully opened, which space will freely accommodate a thread or threads and prevent 45 same being nipped by the latch.

In the production of an ordinary knitted stitch by a needle as last described, the needle is raised to clear an existing loop *a* beneath the latch 2b and new thread *b* is fed into the 50 hook 3. When making such stitch, the tip of the lowered or opened latch is spaced from the needle shank so that, as the needle is lowered or retracted, the existing loop *a* will pass beneath the latch and, during the lowering 55 or retracting movement of the needle, close said latch upon the needle hook and be cast off, a loop of the new thread *b* meanwhile being drawn through the cast off loop in the customary manner.

60 To make a locked or tied stitch, the needle is raised or projected to a greater height or distance than is the case when producing an ordinary knitted stitch, the lowered or open latch is moved into a position wherein its tip 65 is spaced from the needle shank and the new

thread *b* is fed in between said lowered latch and the shank, i. e. into the aforesaid substantially elliptical space 17.

In Figure 8 a needle is shown fully or almost fully raised or projected with the old loop *a* cleared below the latch and new thread *b* fed into the space 17 between said latch and the needle shank. During the downward movement or retraction of the needle, the open latch 2b is pressed by a suitable presser 70 4a so that its pointed tip 2d enters the saw-cut 16 in the needle shank, and the old loop *a* on the needle passes up over said open latch as shown in Figure 9, and into the needle hook as in Figure 10. During this part of the motion a loop of the new thread *b* is drawn 75 through the old loop *a*, and on the continued downward motion said loop of new thread functions to raise the latch 2b to the closed position on the needle hook 3 and passes over 80 said closed latch to be cast off the needle to the position shown in Figure 11. Thus it will be appreciated that the loop of new thread instead of as in the case of an ordinary stitch being retained upon the needle, is cast off and 85 the old loop is still retained on the needle, said new loop being drawn through and also passed around said existing loop and becoming tied thereon, as before-described with reference to the needle having a flexible or 90 resilient latch.

The displacement of the fully open latch 2b to a second open position wherein its tip is clear of the needle shank for permitting the thread *b* to pass into the space 17, can be 95 positively effected at the required times by causing a cam element 18 or other suitable means to coact with the laterally projecting or cranked portion 2e of the latch adjacent to its pivot. It is, however, to be understood 100 that other means may be provided for ensuring that the tip of the open latch is spaced from the needle shank when required.

The pointed tip 2d of the latch may, if desired, be slightly curved so that when the 110 latch is in the raised or closed position with the extremity of the hook buried in the cup 2e, said curved tip 2d coincides approximately with the curvature of the needle hook 3.

115 Preferably, the circumferential dimension of the needle at the hook 3 when the latch 2b is closed thereon is somewhat greater than the circumferential dimension of the needle shank at 1b, the circumferential dimension at 1b being also preferably slightly greater 120 than that at the part 1c when the latch is fully lowered or opened.

125 It is to be understood that when plain or ordinary knitted fabric is to be produced without locked or tied stitches, the needle cam mechanism appertaining to said locked or tied stitches is thrown out of operation; and in the case of a circular knitting machine this may be effected by mounting the locked stitch cam device B in a removable or 130

displaceable manner and associating means for automatically moving said cam device into and out of operation at the required times. The thread feed 6 associated with the locked stitch cam device B is also advantageously moved into and out of operation in synchronism with said cam device.

The construction and mode of operation of the needle latch presser may be varied in many ways without departing from the scope 10 of the present invention.

I claim:—

1. A needle applicable for use in the production of knitted fabrics, comprising a shank, a hook on said shank, a pivoted latch, and said latch having two open positions, one wherein the free end or tip thereof is maintained spaced from the needle shank so as to permit of thread being fed or drawn between the latch and shank, and a second open 20 position wherein said end or tip coacts with said shank.

2. A needle applicable for producing knitted fabrics, comprising a shank, a hook on said shank, a latch pivoted to said shank, said latch having two open positions, one wherein the tip of the latch is spaced from the shank to permit of thread being fed or drawn between the open latch and shank, and a second 30 open position wherein the latch tip coacts with the shank and provides an enclosed space between the latch and shank adapted to freely to accommodate the thread fed or drawn therein.

3. A knitting needle comprising a shank, a hooked extremity to said shank, a latch pivoted to said shank, said latch being flexible or resilient and adapted to be pressed against its own resilience from the normal open position 40 wherein the latch tip is spaced from the needle shank to a second open position wherein said tip coacts with a recess in said shank.

4. A knitting needle comprising a shank, a hooked extremity to said shank, a rigid or inflexible pivoted latch, said latch when fully 45 open coacting at its tip with a recess in the shank and providing an enclosed space between latch and shank for freely accommodating thread, and said latch being pivotally 50 displaced to permit of thread being fed or passed thereunder by applying pressure to a part of the latch adjacent to its pivot.

5. A knitting needle comprising a shank, a hooked extremity to the shank, a latch pivoted to said shank, the shank having two portions of increased width or circumferential size spaced one below the other, a saw-cut in the uppermost of said wider shank portions accommodating that part of the latch adjacent to the pivot, a saw-cut or recess in the lower of the two wider shank portions adapted freely to accommodate the tip of the latch when said latch is in the lowered or fully open position, a laterally projecting portion on 65 the latch adjacent to the pivot, said laterally

projecting portion being adapted when the latch is in the fully open or lowered position to project beyond the inner face of the needle shank, and said laterally projecting portion being operated upon at predetermined times so as pivotally to displace the latch to a position wherein the latch tip is spaced from the needle shank so as to permit of thread being fed or drawn into a space between said latch and the needle shank.

6. A needle as claimed in claim 5 for producing knitted fabric, in combination with means for pressing the latch into the fully open position with its tip coacting with a recess in the needle shank subsequently to moving said latch to a position wherein the latch tip is spaced from the needle shank for permitting thread being fed or drawn between said latch and needle shank.

7. A needle as claimed in claim 2 in combination with means for feeding thread at predetermined times below the open latch and passing same between said latch and the needle shank, means for pressing the latch over said thread into engagement with the shank, means operating the needle so as to pass an old thread loop on the needle over said pressed latch and the thread retained thereunder into the needle hook, and means for subsequently removing the pressure from the latch and permitting the thread loop retained thereunder to close said latch on to the needle hook and pass off the needle so as to embrace the old thread loop and become tied thereon.

8. A needle as claimed in claim 2 functioning to produce knitted fabric by the following sequential operations, in combination with cam means constructed to (1) project the needle to an extent sufficient to permit feeding of thread within the needle hook and produce an ordinary knitted stitch, (2) project the needle to a comparatively greater extent to cause thread to be fed or drawn between an open needle latch and the needle shank, (3) pressing the open latch to cause a old thread loop to be drawn over said pressed open latch into the needle hook, and (4) rendering said latch-pressing means inoperative and causing a loop of new thread to be passed off the needle over the old thread loop and become locked or tied thereon.

ROBERT KIRKLAND MILLS.
